UNITED STATES PATENT OFFICE.

WALTER S. BICKLEY, OF CHESTER, PENNSYLVANIA.

DESIGN FOR A WATCH-CHARM.

SPECIFICATION forming part of Design No. 34,125, dated February 26, 1901.

Application filed January 3, 1901. Serial No. 42,024. Term of patent 7 years.

To all whom it may concern:

Be it known that I, WALTER S. BICKLEY, a citizen of the United States, residing at Chester, in the county of Delaware, State of Pennsylvania, have invented and produced a new and original Design for Watch-Charms, consisting of a stockless anchor, of which the following is a specification, reference being had to the accompanying drawing, forming part thereof.

The figure illustrating my design is a perspective view thereof.

As shown in the drawing, the leading or material feature of my design consists of the peculiar-shaped fluke 1, with the shank 2, connected therewith. The flukes have a flat or broad base 3, extending outwardly from the

flukes. 4 is a flat portion between the flukes in which a groove is formed. The shank 2 is shown as extending into the groove 5, and an enlarged portion 6, formed at the base of the shank and being in said groove or slot.

Having described my invention, what I claim as new, and desire to secure by Letters Patent, is—

The design for a watch-charm, as herein shown and described.

In testimony whereof I have hereunto set my hand to this specification in the presence of two witnesses.

W. S. BICKLEY.

Witnesses:

CHARLES PALMER,

FRANK J. PERKINS.
